Term of patent 14 years

Int. Cl. D26—05

U.S. Cl. D48—23 A

FIG. 1

FIG. 3

FIG. 1 is a perspective view of a ceiling mounted fluorescent fixture showing my new design;

FIG. 2 is a side elevational view of the fixture of FIG. 1; and

FIG. 3 is a bottom view thereof.

The reverse side of the fixture is identical with the side shown in FIG. 2. The major sections of the side walls are transparent as is the bottom. The upper securing portion is opaque.

I claim:

An ornamental design for a ceiling mounted fluorescent fixture, as shown and described.
